UNITED STATES PATENT OFFICE.

ERNST TROIKE, OF SANDUSKY, OHIO, ASSIGNOR OF ONE-FOURTH TO PAUL TROIKE, OF SANDUSKY, OHIO.

MAGNETO-ELECTRIC MACHINE.

No. 926,368.

Specification of Letters Patent.

Patented June 29, 1909.

Application filed November 30, 1908. Serial No. 465,295.

To all whom it may concern:

Be it known that I, ERNST TROIKE, a subject of the Emperor of Germany, residing at Sandusky, in the county of Erie and State of Ohio, have invented certain new and useful Improvements in Magneto - Electric Machines, of which the following is a specification.

This invention relates to that class of electric generators known as bipolar magneto-electric machines, and has particular reference to certain specific details of improvement whereby the same is adapted especially for use in connection with hydrocarbon engines to cause ignition of the mixed charges of air and hydrocarbon fuel. It is to be understood, however, that the invention is not limited to such specific use, but is adapted also for use wherever it is desired to make use of an electric spark for lighting or ignition purposes.

The invention is adapted especially for the production of a strong hot spark and as the result of a comparatively slow movement of the armature.

I am aware that oscillating armatures in magneto-electric machines have heretofore been proposed, but in my experience I have ascertained that such devices are generally unsatisfactory as heretofore contemplated.

The machine constituting the subject-matter of this invention is designed primarily for use in connection with my improved hydrocarbon engine constituting the subject-matter of a separate application filed of even date herewith, Serial Number 465,294.

For a full understanding of the invention reference is to be had to the following detail description and to the accompanying drawings, in which—

Figure 1 is a vertical longitudinal sectional view; Fig. 2 is a vertical end view of the device, and Fig. 3 is a detail cross section.

Throughout the following detail description and on the several figures of the drawing similar parts are referred to by like reference characters.

Referring specifically to the drawings, I have shown at 10 a base plate of any suitable material, preferably brass, which is connected to the support and upon which the several features constituting this invention are mounted. A pair of cast iron pole-pieces 11 are mounted upon the upper side of the base 10 and are provided with oppositely disposed

concave cylindrical faces 11'. Rigidly and permanently connected to said pole-pieces are a plurality of magnets 12 and 13, the poles of which terminate adjacent to the lower edges of the pole-pieces 11 and proximate to the base 10. The said faces 11' are substantially concentric and journaled for operation therein is an armature comprising an iron core 14, in the form of a spool upon which a coil of insulated wire is wound, one end of the wire being connected to said core. The armature at each end is of peculiar construction and comprises a substantially flat disk 15, preferably of brass and in which is tapped centrally a trunnion 16. Surrounding the trunnion 16 adjacent the outer face of the disk 15 is a disk of insulation having a flange 17' and upon which disk adjacent said flange 17' is a ring or tire 18 of suitable conducting material such as brass. Another disk of insulation 19 retains said ring 18 and is secured to the disk 17 and plate 15 in any suitable and permanent manner, as by screws. The construction of the armature is substantially the same at both ends, but the trunnion 16' is longer than the trunnion 16 and is provided at its outer end with an operating arm 21 for operation thereof from any suitable source of power such as the crank shaft of an engine and whereby the armature is given an oscillation or rotation through a portion of a circle. The trunnions 16 and 16' are journaled in bearing plates 22 rigidly secured to the base plate 10 and pole-pieces 11 in any suitable manner. The plates 22 are provided with means for supplying oil to the trunnions and for the retention thereof in any convenient manner.

The outer end of the wire 23 is passed through the disk 15 from which it is insulated by means of a thimble 24 and is attached upon the inner surface of the ring 18. A brush 25 is suitably mounted for contact with said ring 18 and is supported radially thereto. The outer end of the brush has connected thereto by binding nuts a conducting wire 26. The disk 15' at the opposite end of the armature is engaged by a secondary brush 27 mounted within a housing 28 carried by a cover plate 29 insulated from but connected to the pole-piece 11 and between the legs of the poles 12. Upon sufficient oscillation of the armature to cause the edge 14' to pass the point 11'' of the pole-piece the electricity generated by the brushes in the man-

ner above indicated will be caused to produce a spark in connection with any suitable sparking devices.

Having thus described the invention, what is claimed as new, is:

The herein described magneto-electric machine, comprising a main support, magnets supported thereon, a pair of pole-pieces associated with the ends of the magnets, an armature journaled for oscillation between said pole-pieces and comprising a core and windings, a pair of disks secured to the ends of the core and inclosing the windings, a disk of insulation at the outer side of one of the said disks, a conductor ring carried by said insu-

lation disk, a thimble of insulation extending through the latter mentioned core disk, the outer end of the winding being passed through said thimble and disk of insulation and connected to said ring, a pair of brushes, one coöperating with one of said disks and the other coöperating with said ring, and a plate of insulation secured to the disk of insulation to retain the said ring thereon.

In testimony whereof I affix my signature 25 in presence of two witnesses.

ERNST TROIKE.
